UNITED STATES PATENT OFFICE.

GILBERT L. BAKER, OF OAKDALE, CALIFORNIA.

POCKET LOCK.

Application filed June 20, 1924. Serial No. 721,308.

This invention appertains to pocket implements capable of being used for a variety of different purposes, and the primary object of the invention is to provide a portable 5 pocket lock which can be readily and quickly applied to doors and windows from the inside of the room for effectively preventing the opening of the door or window from the outside of the room.

Another primary object of the invention is to provide a portable pocket lock particularly adaptable for travelers which can be readily applied to the usual type of doors and which embodies means for engaging 10 between the door and door frame and means for engaging the inner face of the door and door frame whereby opening of the door from the outside by burglars and the like will be prevented, the device being 15 so constructed as to permit the use thereof on doors of different thickness and doors with varying spaces between their forward edge and the door frame.

A further object of the invention is the 20 provision of a portable pocket lock embodying a frame for slidably receiving a plurality of pivoted leaves, the leaves having means formed on their inner edges for gripping a door and a door frame, the frame of 25 the implement having means for rigidly engaging the leaves and the inner face of the door and door frame, the leaves being so arranged as to permit any number of the same 30 to be used between the door and door frame according to the space therebetween.

A further object of the invention resides 35 in the formation of the leaves whereby the same can be readily used for different purposes, such as a comb and ruler, bottle 40 opener, wrench, and the like.

A further object of the invention is the 45 provision of novel means for mounting a finger-nail cleaning implement on the implement frame, whereby the finger-nail cleaning 50 implement can be moved to a hidden inoperative position and to an exposed operative position.

A still further object of the invention is 55 to provide a novel combination pocket implement of the character described which will be durable and efficient in use, one which will be simple and easy to manufacture, and one which can be placed upon the market at a small cost.

With these and other objects in view, the 55 invention consists in the novel construction, arrangement, and formation of parts, as will be hereinafter more specifically described, claimed, and illustrated in the accompanying drawings, in which drawings,— 60

Fig. 1 is a top plan view of the improved 65 implement showing the same in use as a door lock, the door and door frame being shown in section,

Fig. 2 is a side elevation of the improved 70 implement showing the same in use as a door lock, the door being shown in edge elevation, the view illustrating the position of the leaves which are not in use;

Fig. 3 is a longitudinal section through 75 the implement taken on the line 3—3 of Fig. 1;

Fig. 4 is a transverse section through the 80 implement taken on the line 4—4 of Fig. 2;

Fig. 5 is a detail end elevation of the 85 implement showing the same in use as a door lock, a fragment of the door and door frame being shown;

Fig. 6 is a side elevation of the improved 90 pocket implement showing one position thereof when the same is not in use;

Fig. 7 is a longitudinal section taken on the line 7—7 of Fig. 6;

Fig. 8 is a transverse section through the 95 implement taken on the line 8—8 of Fig. 6 illustrating the means of mounting the frame of the implement on the leaves and showing the nail cleaning instrument carried by the frame; and

Fig. 9 is a side elevation of the improved 100 instrument showing the various leaves spread out to illustrate the formation thereof.

Referring to the drawings in detail, 105 wherein similar reference characters designate corresponding parts throughout the several views, the letter A generally indicates the improved portable pocket lock which comprises a frame 10 preferably formed of sheet metal of the desired gage 110 and bent into the desired shape. The frame 10 is substantially U-shaped in cross-section and includes the outer longitudinal extending wall 11 and the spaced parallel walls 12 which are provided with the longitudinally 115 extending slots 13 for a purpose which will be hereinafter more fully described. The outer wall 11 is also provided with a longi-

tudinally extending slot 14 for the reception of the manipulating finger-piece 15 of the finger-nail cleaning blade or instrument 16. By grasping the finger-piece 15 the blade 16 can be moved into an operative position, as shown in Figs. 1 to 3 inclusive, or moved into an inoperative unexposed position, as shown in Fig. 6. This finger-nail blade is adapted to be used both as a cleaning and finger-nail filing instrument and one face of the blade can be roughened as at 17 to form the file.

The frame 10 supports a plurality of leaves which serve a variety of purposes. However the main purpose of the leaves is to cooperate with the frame 10 to form a door or window lock. As shown I have provided an intermediate flat leaf 20, and pairs of side leaves 21 and 22 and 23 and 24 which lie on the opposite sides of the intermediate leaf 20. All of these leaves preferably but not necessarily converge toward their inner ends and the leaves are pivotally connected together and to the frame 10 by means of a pivot pin 24'. This pivot pin 24' also extends through the slots 13 in the side walls 12 of the frame 10 thereby permitting the frame to be adjusted relative to the leaves. The pivot pin has also mounted thereon a loop 25 which permits the pocket implement to be attached to a key-ring, watch-chain, or the like, and when the finger-nail cleaning blade 16 is moved to its operative position this loop 25 can be moved down in rear of the finger piece 15 for holding the blade against inward movement. The forward ends of the side leaves 21 and 22 and the forward ends of the side leaves 23 and 24 are provided with right-angularly bent laterally-directed biting teeth 26 for engaging the door and for biting into the door frame. One longitudinal edge of each leaf is provided with a plurality of equidistantly spaced teeth 27 for a purpose which will be hereinafter more fully described. It is to be noted however that the teeth 27 of the side leaves 21, 22, 23, and 24 stop short of the inner and outer ends thereof, while the teeth on the intermediate leaf 20 extend the full length thereof to permit this leaf to be used as a pocket comb. The other longitudinal edge of the intermediate leaf can be provided with graduations as indicated by the reference character 28 whereby the same can be used as a ruler.

The frame 10 at one end thereof has formed integrally with the outer wall 11 a projecting head 29 which is provided with a depending foot 30 having a slot 31 therein defining spaced legs 32.

In use of the improved implement A as a door lock the desired number of leaves according to the space between the door and door frame is placed between the door D and the door frame F, after which the door

is swung to its closed position. The teeth 26 on the leaves on one side engage the door while the teeth of the leaves on the other side will bite into the door frame. The frame 10 of the implement can now be slid along the leaves until the head 29 engages the door and door frame, after which the frame 10 of the implement can be swung until the foot 30 engages between the teeth 27 of the leaves being used, as clearly shown in Figs. 2 to 4 inclusive, a leg 32 of the head lying on each side of the leaves. The leaves which are not being used can be swung down at right angles to the leaves in use and the frame 10. By this construction it is obvious that the implement can be adjusted according to the thickness of the door and also to the space between the door and door frame.

While I have shown and described the implement as being used as a door lock, it is to be also understood that the same can be used as a window lock by inserting the leaves between the midrails of the upper and lower sashes and by swinging the frame with the foot 30 into engagement with the outer faces of the midrails.

The leaf 21 is provided with a notch 35 for permitting the instrument to be used as a wrench for small bolts, nuts, and the like, and one edge of this leaf can be provided with a cutting surface 36 to cooperate with the edge of the leaf 22 to form a cigar cutter. The leaf 22 is provided with a polygonal shaped opening 37 for permitting this leaf to be used as a wrench for small nuts such as used in magnetos, carburetors, and the like. The leaf 24 has one edge thereof shaped as at 38 to form a bottle opener and for pulling the top off of cans, jars, and the like. The leaf 23 is provided with an alligator wrench 39 for adjusting small bolts, nuts, and the like such as is used in magnetos, carburetors, and the like.

From the foregoing description it can be seen that I have provided an improved pocket implement of a single durable character, which can be used for a number of different purposes.

Changes as in detail may be made without departing from the spirit or the scope of this invention; but

What I claim as new is:—

A portable pocket lock for a door, window, or the like, comprising a frame substantially U-shaped in cross-section including spaced parallel side walls with longitudinally extending slots therein, a plurality of leaves, means pivotally connecting the leaves together, said means extending through the slots in the side walls of the frame for pivotally and slidably connecting the frame with the leaves, door and door frame biting teeth formed on the outer ends of the leaves, adjusting teeth formed on certain longitudi-

nal edges of the leaves, and a depending bifurcated foot formed on the frame for engaging between the teeth on the longitudinal edges of the leaves for holding the frame in

an adjusted position on the leaves, the foot extending in parallel relation to the door and door frame when the frame is in its ad-

justed position on the leaves, the frame forming means for receiving the leaves, when the device is being carried in the 10 pocket.

In testimony whereof I affix my signature.

GILBERT L. BAKER.
